[57] **CLAIM**

The ornamental design for a “selective call receiver”, as shown and described.

DESCRIPTION

FIG. 1 is a front elevational view of a “selective call receiver” showing a first embodiment of our new design;

FIG. 2 is a top plan view of FIG. 1;

FIG. 3 is a rear plan view of FIG. 1;

FIG. 4 is a left side elevational view of FIG. 1;

FIG. 5 is a right side elevational view of FIG. 1; and

FIG. 6 is a bottom elevational view of FIG. 1;

FIG. 7 is a top, right and front perspective view of FIG. 1; FIG. 8 is a front elevational view of a “selective call receiver” showing an alternate embodiment of our new design;

FIG. 9 is a top plan view of FIG. 8;

FIG. 10 is a rear plan view of FIG. 8;

FIG. 11 is a left side elevational view of FIG. 8;

FIG. 12 is a right side elevational view of FIG. 8; and

FIG. 13 is a bottom elevational view of FIG. 8; and,

FIG. 14 is a top, right and front perspective view of FIG. 8.
